(57) **CLAIM**

The ornamental design for a snowmobile access panel, as shown and described.

DESCRIPTION

FIG. 1 is a front left perspective view showing a snowmobile access panel according to our design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and,

FIG. 7 is a front elevation view thereof.

The broken lines immediately adjacent the shaded areas represent boundaries of the claimed design while all other broken lines illustrate unclaimed portions of the snowmobile access panel. The broken lines form no part of the claim.

1 Claim, 7 Drawing Sheets
